UNITED STATES PATENT OFFICE

2,362,154

CHEESE PRESS

Edward B. Patrick, Rock, W. Va.

Application November 24, 1942, Serial No. 466,759

1 Claim. (Cl. 100—55)

The present invention relates to new and useful improvements in cheese presses, particularly of the domestic type, and has for its primary object to provide, in a manner as hereinafter set forth, a device of this character comprising novel means for firmly supporting and retaining the hoop and the perforated bottom.

Other objects of the invention are to provide a cheese press of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of a cheese press constructed in accordance with the present invention.

Figure 2 is a view in horizontal section through the device, taken substantially on the line 2—2 of Figure 1.

Figure 3 is a view in vertical section, taken substantially on the line 3—3 of Figure 1.

Figure 4 is a top plan view of the portion of the base on which the hoop and perforated bottom are mounted.

Figure 5 is a detail view in vertical section, taken substantially on the line 5—5 of Figure 1.

Figure 6 is a top plan view of the follower.

Referring now to the drawings in detail, it will be seen that the embodiment of the invention which has been illustrated comprises a supporting stand which is designated generally by reference numeral 1. The stand 1 includes metallic legs 2 of angular cross section having mounted on their upper end portions a top 3. Mounted on the lower portions of the legs 2 is an elevated base 4 having extending vertically therethrough and depending therefrom a centrally located drain tube 5.

Fixed on the base 4 is a ring 6 of suitable material. Extending inwardly from the ring 6 are radial ribs 7. The inner ends of the ribs 7 are spaced from the drain tube 5, as illustrated to advantage in Figure 4 of the drawings.

A hoop 8 is removably mounted on the base 4 in the stand 1. The hoop 8, as usual, is open at its upper and lower ends and said hoop comprises, on its lower end, an internal flange 9 which fits around the ring 6. At its upper end, the hoop 8 is provided with an external flange or bead 10. From the foregoing, it will be seen that the ring 6 constitutes means for retaining the removable hoop 8 in position on the base 4.

Removably mounted in the lower portion of

the hoop 8 is a bottom 11 having perforations 12 therein. As best seen in Figure 3 of the drawings, the perforated bottom 11 is supported in spaced relation to the base 4 by the flange 9, the ring 6 and the radial ribs 7. Thus, drainage to the tube 5 is provided.

A removable follower 13 is operable in the hoop 8. The follower 13 includes an integral, centrally located upstanding socket 14, the purpose of

which will be presently set forth.

A nut or the like 15 is fixed on the top 3 of the supporting stand 1. A pressure screw 16 is threadedly mounted in the nut 15, said pressure screw passing downwardly through the top 3. On its upper end, the screw 16 is provided with a T handle 17. At its lower end, the screw 16 terminates in a ball head 18 which is engaged in the socket 14 for operatively and detachably connecting said screw to the follower 13.

In use, the perforated bottom 11 is placed in the hoop 8 and a disk of suitable fabric is placed on said bottom. The hoop 8 is then lined with the fabric, after which the curd is packed in said hoop. A fabric disk is then placed on the curd

and the follower 13 is mounted thereon in the hoop 8. The assembly is then positioned in the stand 1 and the screw 16 is engaged in the socket 14 of the follower 13. Of course, the pressure is then applied by turning the screw 16 downwardly

in an obvious manner.

It is believed that the many advantages of a cheese press constructed in accordance with the present invention will be readily understood, and although a preferred embodiment of the device

is as illustrated and described, it is to be understood that changes in the details of construction may be resorted to which will fall within the scope of the invention as claimed.

What is claimed is:

40. In a cheese press, in combination, a flat horizontal base plate having a plane upper surface and provided with a central drain tube, a hoop comprising a vertical open-ended cylinder having a flat horizontal inturned annular flange at its lower end flatly resting on the base plate concentric with said drain tube, a flat annular ring fixed on the base plate and snugly fitting within said flange, said ring having a plurality of similar equally-spaced radial ribs projecting inwardly

45 therefrom and terminating outwardly of the drain tube, said ribs being free of connections except at their outer ends with the ring, the flange, ring and ribs being of similar uniform thickness throughout, and a flat perforated disk

50 removably fitted in said hoop and resting horizontally on the flange, the ring and the ribs in uniformly spaced relation to the upper plane surface of the base plate.
